FLAME CONTROL MEANS FOR OIL BURNERS

Harry K. Winters, San Francisco, Calif., assignor
to Ray Oil Burner Co., San Francisco, Calif., a
corporation of California

Application May 15, 1950, Serial No. 162,099

5 Claims. (Cl. 158—76)

1

This invention relates to flame control means for oil burners and particularly to means for controlling the flame pattern of high pressure oil burners.

It is conventional practice in high pressure oil burners to provide a burner tip for delivering oil under pressure and to supply air under pressure in a somewhat circular pattern surrounding the burner tip and in many cases to interpose vanes in the path of air flow to impart a swirling motion thereto and create a twisting or swirling action which aids in the mixture of oil and air and thus contributes to efficient combustion. The flame pattern thus created is of conical contour diverging from the nozzle tip and into the fire box of the furnace with which the burner is used.

The shape of the fire box of furnaces varies considerably and it is desirable that a burner be capable of adjustment to produce a flame pattern varying from long and narrow to short and wide so that the flame can be made substantially to fill the area of the fire box in which combustion takes place to provide even distribution therein and to avoid the undesirable impingement of flame against the wall of the fire box opposite the burner or at other points in the fire box.

Present attempts at flame shaping consist mainly of changing the oil nozzle spray angle, through nozzle design, without changing the air delivery pattern. This method is ineffective because, if the oil spray cone angle is narrower than the air delivery cone angle, poor mixing of the air and oil results with consequent poor combustion and efficiency. If the oil spray angle is wider than the air delivery cone angle, the oil spray is entrained by the air and assumes the shape of the air pattern, thereby losing any effective flame shaping properties due to the oil spray angle alone.

In some devices, attempts are made to shape the flame by introducing a cylindrical envelope of air directly around the nozzle to produce a long narrow flame. This air is not twisted or spun so that the mixing of the air and oil spray is adversely affected. Also, sufficient air for combustion must be introduced into this cylindrical envelope with the effect that the air passing through any outer vanes and forming a diverging conical envelope becomes excess air and lowers the combustion efficiency. The present invention differs from the attempts last described in that it employs a swirling flow of air for admixture with the oil spray and an additional flow of air

2

in a substantially cylindrical path which acts to regulate the flame pattern without interfering with the admixture of oil and air which contributes to efficient combustion.

5 It is the object of the present invention to provide a high pressure oil burner with means for varying the cone angle or flame pattern without materially effecting the ratio of oil and air which contributes to perfect combustion. Further and 10 more specific objects and advantages of the invention and the manner in which these objects and advantages are accomplished are set forth in the following specification wherein reference is made in detail to the accompanying drawing.

15 In the drawing:

Fig. 1 is a central longitudinal section through the delivery portion of an oil burner embodying the present invention.

Fig. 2 is a sectional view taken on the line 20 II—II of Fig. 1, and

Fig. 3 is a sectional view with burner tip and burner cup removed of the forward portion only of the burner taken on the line III—III of Fig. 2.

25 In order to illustrate the principles of the present invention, only those portions of the burner directly pertinent thereto have been shown while the means for delivering oil into the air under pressure to the burner and the ignition means therefore may be of any conventional form and 30 are not necessary to an understanding of the flame control means herein disclosed.

In Fig. 1 of the drawing, a conventional burner tip is shown at 10 as fitted to the end of a pipe 11 through which oil is delivered from a high pressure oil pump not shown. A barrel 12 surrounds the burner tip and air from a blower, not shown, is introduced into the barrel and flows out of its open end for admixture with the oil delivered by the burner tip. Also surrounding the tip and 35 interposed between the tip and the barrel is a cup 13 concentric with the tip and the barrel and closed at its inner end to cause the air to pass in the annular space between the barrel and the cup. A flange 14 fixed to the open end of the 40 barrel has an inwardly tapered surface 15 tending to direct the flow of air inwardly against the diverging spray of oil emanating from the burner tip.

45 It is also common practice to impart a swirling 50 action to the air by twisted vanes interposed in its path of flow in order to create good mixture of oil and air to enhance combustion. For this latter purpose, the present invention includes a collar 16 interposed between the cup 13 and the barrel 12 and carrying a plurality of inwardly

projecting curved vanes 17, the arrangement and configuration of which is illustrated in Figs. 2 and 3.

In order to control the flame pattern or cone angle of the flame, the collar 16 of the present invention is somewhat smaller in diameter than the inside diameter of the barrel 12 so that a space or annular passage 18 through which air may flow surrounds the vanes 17 which impart the twisting or swirling action to the main volume of air. The volume of air which passes through the annular space 18 may, according to the present invention, be controlled by moving the collar 16 forwardly toward the open end of the barrel 12 or rearwardly away from said end of the barrel. When moved to an extreme forward position, the collar 16 abuts a shoulder 19 of the flange 14 to prohibit the flow of any air through the space 18 and as the collar is moved rearwardly away from the flange 14, the volume of air passing through the annular space 18 is increased. A typical conical flame pattern is indicated at 20 in Fig. 1 and the angle indicated at "a" is that referred to as the cone angle of the flame pattern. Such a flame pattern is created as a result of the oil sprayed from the burner tip and the swirling flow of air controlled by the vanes 17. However, the cone angle "a" may be varied by regulating the volume of the cylindrical envelope of air flowing through the annular passage 18, an increased flow of this air tending to compress the cone or reduce the angle "a" and, therefore, elongate the flame pattern. This has been found a desirable way of varying the flame pattern because the swirling action of the main volume of air combining with the oil spray is not interfered with and the means for controlling the flame pattern is extremely simple mechanically.

One simple form for controlling the adjustment of the collar 16 is illustrated in Figs. 1 and 2 as a pair of sliding rods 21 threaded at one end into lugs 22 formed on the collar. The rods may be guided through bearings 23 on the cup 13 and may extend through the rear wall of the barrel 12, as shown, where they project and carry suitable knobs 24 for manual adjustment of the collar.

It is desirable that the various parts at the delivery end of the burner be maintained in concentric relationship and in the present case, the vanes 17 bear against the exterior of the cup 13 and a plurality of small lugs 25 extend radially from the exterior of the collar 16 for guiding engagement with the interior of the barrel 12. The burner tip is held in concentricity with the cup 13 by the pipe 11 which passes through a suitably centered opening in the rear wall of the cup. The cup is illustrated as having several small openings 26 adjacent its rear end which admit to the interior of the cup just sufficient air to purge it of any combustible mixture which might collect behind the burner tip but this quantity of air is not intended materially to effect combustion.

I claim:

1. In an oil burner, a nozzle for spraying oil under pressure, a cup-like member surrounding the nozzle, a barrel surrounding and spaced from the cup-like member, means to deliver air through the barrel for mixture with the oil, a set of annularly arranged deflector vanes to impart a swirling action to the air arranged

exteriorly on the cup, and a collar supporting said vanes on the inner surface thereof, said collar being spaced from the interior of the barrel to provide a circular passage for air.

5 2. In an oil burner, a nozzle for spraying oil under pressure, a cup-like member surrounding the nozzle, a barrel surrounding and spaced from the cup-like member, means to deliver air through the barrel for mixture with the oil, a set of annularly arranged deflector vanes to impart a swirling action to the air arranged exteriorly of the cup, a collar supporting said vanes on the inner surface thereof, said collar being spaced from the interior of the barrel to provide a circular passage for air and means for varying the size of said passage.

20 3. In an oil burner, a nozzle for spraying oil under pressure, a cup-like member surrounding the nozzle, a barrel surrounding and spaced from the cup-like member, means to deliver air through the barrel for mixture with the oil, a set of annularly arranged deflector vanes to impart a swirling action to the air arranged exteriorly of the cup, a collar supporting said vanes on the inner surface thereof, said collar being spaced from the interior of the barrel to provide a circular passage for air, a flange adjacent the end of the barrel, and means to adjust said collar to and away from said flange to vary the size of said circular passage.

25 4. In an oil burner of the character described comprising an oil spraying nozzle, a cup surrounding the nozzle, a barrel surrounding and spaced from the cup, means for delivering a stream of air through the barrel for mixture with the oil, air stream splitting means within the space between the cup and barrel, means on one side of the air splitting means to cause a part of the air to flow therefrom in a conical pattern and means on the other side of the air splitting means to direct the remainder of the air stream against the conical pattern to vary its shape.

40 5. In an oil burner of the character described comprising an oil spraying nozzle, a cup surrounding the nozzle, a barrel surrounding and spaced from the cup, means for delivering a stream of air air through the barrel for mixture with the oil, air stream splitting means within the space between the cup and barrel, means on one side of the air splitting means to cause a part of the air to flow therefrom in a conical pattern, means on the other side of the air splitting means to direct the remainder of the air stream against the conical pattern to vary its shape, and adjusting means operatively associated with the air splitting means to adjust the amount of air flowing against the conical pattern.
